FIG. 1

FIG. 2

INVENTOR.

CLARA A. PALMER

BY

Richard P. Cardew

AGENT

UNITED STATES PATENT OFFICE

163,814

PRAM SUIT

Clara A. Palmer, Duluth, Minn., assignor to North
Shore Manufacturing Co., Duluth, Minn., a cor-
poration

Application November 8, 1950, Serial No. 12,903

Term of patent 14 years

(Cl. D3—17)

To all whom it may concern:

Be it known that I, Clara A. Palmer, a citizen of the United States of America, residing at Duluth, in the county of St. Louis and State of Minnesota, have invented a new, original, and ornamental Design for a Pram Suit, of which the following is a specification, reference being had to the accompanying drawing, forming a part thereof.

In the drawing:

Fig. 1 is a front view of a pram suit showing my new design.

Fig. 2 is a rear view of Fig. 1.

I claim:

The ornamental design for a pram suit, as shown and described.

CLARA A. PALMER.
